UNITED STATES PATENT OFFICE.

RUSSELL I. RHODES, OF ATTLEBORO, MASSACHUSETTS, ASSIGNOR TO THE MASON BOX CO., A CORPORATION OF MASSACHUSETTS.

FOLDING OR COLLAPSIBLE BOX.

1,096,460.

Specification of Letters Patent. Patented May 12, 1914.

Application filed November 4, 1913. Serial No. 799,190.

To all whom it may concern:

Be it known that I, RUSSELL I. RHODES, citizen of the United States, residing at Attleboro, Massachusetts, have invented certain new and useful Improvements in Folding or Collapsible Boxes, of which the following is a specification.

My invention relates to knock-down or folding boxes, and has among others for its objects to provide a box of simple, durable, economical and efficient construction which will have a high degree of strength and rigidity and serve to fully protect the contents during shipment.

The invention includes the novel features of construction and arrangement and combination of parts hereinafter described and particularly defined by the appended claim.

In order that my invention may be better understood, I will explain it by aid of the accompanying drawings which illustrate an embodiment of the invention and in which—

Figure 1 is a plan view of one of the blanks from which the box is made; and Fig. 2 a similar view of the other blank. Fig. 3 is a sectional view; and Fig. 4 is a view with the top and bottom opened out.

As shown in these drawings, I prefer to construct the box of two blanks or pieces of sheet material which may be plain stiff cardboard or pasteboard, or corrugated board as found desirable. The blank shown in Fig. 1 is designed to form one side 1 (which for convenience I will term the back), and the top and bottom 2 and 3. These are, however, duplicates of each other, and they are provided with flaps 2^a and 3^a. These several portions are preferably formed by scoring the blank along the lines *a*—*a* and *b*—*b* to facilitate folding. The other blank indicated in Fig. 2 comprises a portion 4 adapted to form the front of the box or side opposite the portion 1, and end forming sections 5 and 6, these being formed by scoring the blanks along the lines *c*—*c*. The front section 4 has integral flap extensions 4^a formed by scoring along the lines *d*—*d*, and the sections 5 and 6 have corresponding flaps 5^a and 6^a likewise formed by scoring along the lines *e*—*e* and *f*—*f*. The sections 5 and 6 have respectively further flaps 5^b and 6^b formed by scoring along the lines *g*—*g*. In

assembling the box, the flaps 5^b and 6^b are secured to the inner face of the back 1, and the flaps 4^a are folded down within the rectangular closure thus formed and against the inner face of the section 4. Thereafter the flaps 5^a and 6^a are folded inward into a position parallel with each other and with the top and bottom edges of the section 4, and the top and bottom portions 2 and 3 folded down and the flaps 2^a and 3^a inserted between the ends of the flaps 5^a and 6^a, and the inner faces of the inwardly turned flaps 4^a, thus forming the complete closure. In order that the flaps may be easily and quickly and securely held in closing positions, I prefer to provide flexible metallic fasteners, as indicated at 7. These comprise plates of foldable metal which are provided with tongues 7^a adapted to penetrate the sheet material, being secured by forcing the tongues through the material and clamping them on the other side. I prefer to secure these plates to the flaps 4^a so that when the flaps are turned downwardly the fastening plates are on the inside of the box, the tongues 7^b thereof projecting upwardly. These tongues, when the top and bottom are brought down in the manner above described, pass within the loops 8 which are simply sheet metal plates or clips secured to the sections 2^a and 3^a near the point of folding, preferably by having tongues forced through the metal and clenched on the inside. When the tongues 7^b have thus been passed through these clips, they can be folded over to retain the top and bottom securely in position.

By providing the flaps 4^a which are folded inward and downward against the inner face of section 4, I provide a double thickness of material at the front edges of the box, and thus a strongly reinforced construction.

Having thus described my invention what I claim is:

A box of the character described comprising a blank scored to form one side section, the top and bottom, and two end flaps, and a second blank scored to form the second side section and two end sections, said end sections having terminal flaps secured to the side section of the first named blank and said side and end sections of said second

blank each having top and bottom extensions or flaps, said flaps being turned back upon the inner face of said side section, metallic fastening tongues on said flaps projecting outwardly therefrom and adapted to coöperate with eye pieces on the outer faces of the flaps of the top and bottom sections so that when fastened the fastening means

of the box lies within said box and between two flaps.

10

In testimony whereof, I affix my signature in presence of two witnesses.

RUSSELL I. RHODES.

Witnesses:

ARTHUR A. WELLER,
AMOS F. PHIPPS.
